FABRIC TAKE-UP MEANS

Le Roy J. Brooke, Norristown, Pa., assignor to Wildman Jacquard Co., Norristown, Pa., a corporation of Pennsylvania

Application January 13, 1958, Serial No. 708,688

5 Claims. (Cl. 66—149)

This invention relates to improvements in take-up means for use in flat type knitting machines, and more specifically, to improvements to bar and strap means for engaging and drawing flat knit fabrics from the needles which are directed toward preventing injury to the knitter due to unintended contact with the fabric engaging hooks of such devices.

It is a general object of the invention to protect the knitter and others from injuries so frequently suffered from the hooks of these take-up means.

A further object is that of protecting against such injuries while still retaining the full utility of the take-up without sacrificing its efficacy as a means by which the fabric may be securely held and also without making it necessary to resort to more than is now required to "hook" the device to a fabric.

In many flat knitting machines, e.g., full-fashioned type hosiery or sweater knitters, the fabric is drawn from the needles or knitting point by resilient pulling means part of which comprises a bar, strap and fabric engaging hooks at points along the bar length. Examples of such means are to be found in United States Patents 1,683,989 and 2,057,199. The hooks which engage the fabric are sharp and the hook opening is such that while they serve admirably for catching the fabric very quickly and without special effort, they are also responsible for a great many ugly scraches and lacerations suffered by the knitter and others who come in contact with them.

According to the instant invention, the hooks of the take-up means are "protected" or guarded in such a way that while the fabric may be impaled on them in virtually the usual way, it is not reasonably possible for a person using or handling the device or even engaging it while working on or about the machine to become injured by a hook. The device itself is modified by the addition of guard means in the nature of preferably resilient, forked, curved members, one fork end at either side of the hook adjacent its point all as will be explained in detail.

The invention will be described more fully by reference to a specific embodiment thereof as illustrated in the accompanying figures of drawing, wherein:

Fig. 1 is a perspective view showing mechanism including the invention as employed.

Fig. 2 is a section showing details of the invention, and Figs. 3 and 4 are views further illustrating the construction of a hook and its guard.

Now referring to Fig. 1, a fabric take-up means to which the invention has been applied includes a bar 10 and a strap 11 which is preferably resiliently drawn in a manner to pull the fabric F from the needles as its stitches are cast off. A plurality of hooks 12 are attached, at least one at either end of the bar, and in many instances, others are interspersed along the bar length. Since each hook and its attendant guard are preferably similar, a description of one unit will suffice.

Referring to Figs. 2-4, the hook 12 has a shank 13, eye 14 and a point 15. The hook is attached to the bar

2

by a screw 16 which passes through the eye and is threaded into the bar.

Normally, these take-up means include the construction described to this point. While the hooks may be readily engaged in the fabric stitches and hold very well, a serious detriment to the whole appliance resides in the fact that the points of the hooks constitute a definite source of danger. It is a most common occurrence for the knitter or others to be scratched or to suffer more serious and ugly lacerations due to accidental contact with these points. These accidents occur both when connecting and disconnecting the take-up bar, and also, at other times since the operator may work at the fabric area of the machine and the hooks are in position to be contacted.

According to the invention a guard is applied to each hook and is comprised as a flat, spring stock member having a connecting base 17 from which extends a forked portion each fork end 18 of which is bent or curved at its end 19 more or less as shown. Each fork end 18 extends toward a plane in front of the hook point and the curved end 19 has a portion at least, which extends as far in the direction of hook opening, or away from the shank, so as to reach at least to a plane of the hook point parallel to the shank and, in a plane generally perpendicular to that, extends to the front of the hook point. Preferably, it extends a little farther than that.

In practice, it is easy enough to engage the fabric on the hook since by pressing a hook and its guard against the fabric while the latter is in a taut condition, the guard will be sprung toward the point of the hook until the fabric is penetrated by the latter. When impaled on a hook, the fabric passes the guard which then springs back to a point covering or protecting position.

In releasing the fabric, the opposite takes place. The hooks are forcibly withdrawn at which time the guard merely springs inwardly if the fabric is taut or if slack, the fabric itself merely finds its way off the point and past the guard.

However, any contact with the hook-guard assembly which would normally result in a minor or more serious laceration, will merely move the bar and hook aside since any reasonable pressure against the guard will do that before the guard ends 18 spring down enough to uncover the hook point. In this regard it must be borne in mind that, due to the nature of a fabric, it is much more easily engaged by the protected hook than is a part of the human anatomy. Actual tests are most convincing of this.

The guard may be formed of round, spring stock as well as of flat, but in any event, the same general shape and dimensions are to be followed. Stiffness of the guard may vary within limits, and, of course, it may be made of relatively rigid stock but then, engagement of the fabric requires more time and/or there may be a chance of missing if a quick hooking action is attempted. Preferably, one should build into the guard enough resistance so that a pressure at the hook area will not be sufficient to encounter the hook point, but nevertheless, not so much that it would become difficult to hook the fabric as required.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In a means for taking up knitted fabric, a bar, a strap and fabric engaging means attached to said bar, said fabric engaging means comprising a plurality of

hook-like members having a point and guard means at either side of each hook adjacent the point thereof for protecting the user of the take-up means without inhibiting easy engagement of the hook with the fabric.

2. Mechanism as defined in claim 1 wherein said guard means comprises a forked spring-like member.

3. Mechanism as defined in claim 1 wherein said guard means comprises a curved spring-like member at either side of the said hook-like member which, when unflexed, extends at least to the plane of the hook point in the direction of the hook opening and in a plane generally perpendicular to that, extends to the front of the hook point.

4. In a means for taking up knitted fabric, a bar, a strap and fabric engaging means attached to said bar, said fabric engaging means comprising a plurality of hook-like members having a point and guard means for each said hook-like member which comprises a fork-like protecting means extending to each side of said hook-like member and projecting beyond the point thereof in the direction of hook opening and in front of that point.

5. In a means for taking up knitted fabric, a bar, a strap and fabric engaging means attached to said bar, said fabric engaging means comprising a plurality of hook-

like members having a point and guard means for each said hook-like member which comprises a fork-like protecting means extending to each side of said hook-like member and projecting beyond the point thereof in the direction of hook opening and in front of that point, said fork-like means being resilient whereby it may be deflected to uncover the hook point when fabric in a taut state is pressed against said hook.
